1 Claim

ABSTRACT OF THE DISCLOSURE

An apparatus for disintegrating leather comprising a scratch roll, and steel bands disposed on the scratch roll and having a plurality of spike shaped projections thereon. The band portions between the projections are wound full width with steel wire to fasten the band to the scratch roll. A pair of feed rolls is positioned adjacent the scratch roll and urged toward each other and a highly elastic push plate is disposed immediately beneath the feed rolls and in opposite relationship to the scratch roll.

The present invention relates to an apparatus for disintegrating chemically pretreated leather to produce collagen fibers.

Leather used as a raw material exists in various forms. Even if chemically treated, the constituent fibers remain firmly bound together. Heretofore, in conventional apparatus for such treatment, it was often observed that when a large piece of leather was fed by feed rolls and pressed against a scratch roll, the spike shaped projections on the scratch roll were immediately subjected to strong impulsive forces, causing damage thereto.

It is an object of the present invention to provide an apparatus for disintegrating leather to produce collagen fibers at high efficiency.

It is another object of the present invention to provide an apparatus for disintegrating leather, the apparatus of this invention comprising a scratch roll which is provided at its outer peripheral surface with steel bands, each band having a plurality of spike shaped projections set therein. The respective band portions between the spike shaped projections are wound the full width of the roll with steel wire to fasten the steel bands to the scratch roll. A pair of feed rolls is positioned to face the scratch roll, and a push plate, made of a high elasticity material, is disposed immediately below the feed rolls in opposite relationship to the scratch roll.

It is another object of the present invention to provide an apparatus for disintegrating leather using two units of the apparatus, the leather fed into the system being disintegrated and carded by the pointed ends of the spike shaped projections and, when undue force is exerted thereon, the leather enters the space between the spike shaped projections and is thereby prevented from being forcibly broken into small pieces. Simultaneously, the pieces of leather which are not completely disintegrated, are permitted to circulate, making it possible to produce long collagen fibers with high efficiency.

Further, the push plate made of a high elasticity material, is effective not only in increasing the efficiency of disintegration by lightly pressing the carded leather further against the spike shaped projections, but also in discharging the disintegrated leather in uniform density.

With the above and other objects in view which will become apparent in the following detailed description, the present invention will be clearly understood in connection with the accompanying drawing, in which:

FIG. 1 is a diagrammatic side elevational view of a

preferred embodiment of the present invention using two units of the apparatus arranged in series;

FIG. 2 is an enlarged sectional view, broken in part, of the apparatus of the present invention; and

FIG. 3 is an enlarged section along the lines III—III of FIG. 2, broken in part, showing the spike shaped projections on the scratch roll.

Referring now to the drawing, a scratch roll 1 is provided at its periphery with steel bands 18, each band having spike shaped projections 17 set therein. The respective band portions between the spike shaped projections 17 are firmly wound the full width with wire 19 to fasten the steel bands 18 to the roll 1.

The plurality of steel bands 18 disposed on the surface 15 of the scratch roll 1 is arranged preferably parallel to the axis of the roll 1, as indicated in FIG. 2, each band extending across the width of the roll 1 and having the spaced projections 17 thereon. At least one steel wire 19 is wound circumferentially on the portions of the bands 20 18 between the adjacent pairs of projections 17, across the entire width of the scratch roll 1 to hold the bands 18 to the surface of the scratch roll.

A pair of feed rolls 2 are urged toward each other and are positioned to face the scratch roll 1. Immediately 25 beneath the feed rolls 2, there is mounted an elastic push plate 3 formed preferably of synthetic resin or steel.

In the leather disintegrating apparatus above described, when chemically pretreated leather, for example, chrome leather, is fed through a hopper 20, and the leather is 30 caught between the feed rolls 2 and pressed against the spike shaped projections 17 on the scratch roll 1, the leather to the most extent is disintegrated, but does not yet achieve a fibrous condition.

The leather, disintegrated by the spike shaped projections 17, is further pressed lightly by the push plate 3 made of a high elasticity material against the spike shaped projections 17, and gradually turns into a fibrous form.

The fibrous mass and the broken pieces of leather are released from the push plate 3 and drop down onto a guide plate 9, as indicated by the downwardly curved arrow at the right hand portion of FIG. 1. The leather substances which are light in weight are thrown by the force of rotation of the scratch roll 1 onto a feed lattice 5, as indicated by the curved arrow pointing to feed lattice 5 at the right hand portion of FIG. 1, and are subsequently fed by another pair of feed rolls 11 to another scratch roll 10.

The scratch roll 10 has the same construction as the scratch roll 1, with the exception that the former has a smaller diameter and smaller spike shaped projections than the latter.

The broken pieces of leather are partially unravelled collagen fiber mass which are conveyed from the feed lattice 5 are pressed by the feed rolls 11 against the scratch roll 10, and are then further pressed lightly against the scratch roll 10 by an elastic push plate 12, and are thereby converted into a fibrous form.

The fibrous mass or broken pieces of leather released from the push plate 12 are screened by a screening plate 15, and only those which are completely in the form of collagen fibers are sent to a feed lattice 14 and from there delivered as products by a toothed guide 16 to a predetermined position.

The fibers which pass through the screening plate 15 average about 0.05 mm. in thickness and about 25 mm. in length. The yield thereof is about 75% of the leather fed.

On the other hand, the pieces of leather which remain on the guide plate 9, without being thrown onto the feed lattice 5, and the pieces of leather which do not pass through the screening plate 15 are returned by a return lattice 6, and lattices 7 and 8, respectively, and are fed again to the scratch roll 1 together with fresh leather.

Feed rollers 4 and 13 are provided, as indicated in FIG. 1.

In the apparatus of the present invention, a cycle of operation, described above, is repeated. Because steel wire 19 is provided circumferentially between the spike shaped projections 17, all of the projections are prevented from piercing the leather fed when the latter is pressed against the former. Consequently, the impulsive force exerted on the spike shaped projections is reduced, thereby preventing the leather from being forcibly disintegrated and preventing the spike shaped projections from being damaged.

As mentioned above in the illustrated embodiment of the present invention, by using two units of the apparatus, the leather fed in, is disintegrated gradually into long collagen fibers. Further, the apparatus is designed so that the leather which is not completely disintegrated is circulated and again fed, together with fresh leather to the scratch roll. Accordingly, leather is always fed to the scratch roll in substantially uniform density, and the impulsive force applied to the spike shaped projections is evenly distributed.

Although an embodiment using two units of the apparatus arranged in series has been described, by way of example, the present invention is not limited thereto and, for example, three or more units of the apparatus may also be used.

I claim:

1. An apparatus for disintegrating leather to produce collagen fibers comprising
a scratch roll,
a plurality of steel bands disposed on the surface of
said scratch roll,

30 241—294

a plurality of spike shaped projections secured to said steel bands spaced apart from each other,
steel wire disposed between said spaced projections on the portions of said steel bands therebetween and wound around said scratch roll the entire width of the latter fastening said plurality of bands,
a pair of feed rolls adjacent said scratch roll urged toward each other, and
a push plate of a highly elastic material disposed immediately beneath said pair of feed rolls and disposed adjacent to and in opposed relationship with said scratch roll.
